UNITED STATES PATENT OFFICE.

FREDERICK G. SARGENT, OF WESTFORD, MASSACHUSETTS.

SELECTIVE WIRELESS-TELEGRAPH APPARATUS.

1,170,680.

Specification of Letters Patent. Patented Feb. 8, 1916.

Application filed October 3, 1914. Serial No. 864,716.

To all whom it may concern:

Be it known that I, FREDERICK G. SARGENT, a citizen of the United States, residing at Westford, in the county of Middlesex and State of Massachusetts, have invented a new and useful Selective Wireless-Telegraph Apparatus, of which the following is a specification.

This invention relates to improvements over my prior inventions set forth in Letters Patent of the United States Nos. 1,091,768 and 1,102,442, patented respectively March 31st and July 7th, 1914.

The principal objects of the present invention are to provide an apparatus for selective radio telegraphing in which the principle of the dial and indicator is used, one rotatable with respect to the other, but in which there need be no characters on the dial; to provide a construction in which the characters sent or received can be indicated by the illumination of corresponding characters located independently of the dial, such corresponding characters being in some cases arranged on the keys of a typewriter which can be used in sending or for recording messages received; also to provide for receiving by telephone; to provide a construction in which with the same rate of rotation a much more rapid rate of transmission can be secured; to provide an improved electric escapement mechanism for controlling the rotation of the dials or indicators; to provide improved hair-spring adjustment for regulating the rotation; and to provide improvements in details and relative arrangements of the several parts.

Reference is to be had to the accompanying drawings, in which—

Figure 1 is a plan of the preferred form of dial and indicator showing the electrical connections diagrammatically; Fig. 2 is a sectional view showing one way in which the contacts can be made by the dial and indicator; Fig. 3 is an elevation of one of the lamps for illuminating the characters shown as constituting a key of a typewriter and

showing its electrical connections; Fig. 4 is a plan of the hair-spring regulating device; Fig. 5 is a plan of a portion of a dial and indicator showing a modified construction, and Fig. 6 is a plan of a portion of a dial showing another modification.

In the form of the invention shown in the first four figures, the apparatus comprises a selector A, an external series of characters B, a sending circuit C, a receiving circuit D, and an aerial E. This selector A is similar to the selector shown in my above mentioned patents, but the indicator connected with it is shown as having four conducting hands 1, 1, 1, 1. In this case, let it be assumed that the dial 2 is stationary and the indicator rotary. The dial is provided with a series of equally spaced contacts 3 shown in Fig. 2, which are adapted to be engaged by springs 4 on the ends of the indicator hands. These contacts are nearly flush with the surface of the dial plate 2 which is made of hard rubber or other insulating material. The distance between the first and the second hands is equal to ninety degrees plus a quarter of the distance between two of the contacts 3. The distance between the second and third and the third and fourth is the same, leaving the distance between the fourth and first hands equal to ninety degrees less three-quarters of the distance between two of the contacts 3. Therefore, if one hand 1 is on a contact as shown in Fig. 1, the next one in advance will be a quarter away in advance of another contact, the next one beyond it, the third hand, will be half-way between two contacts, and the fourth hand will be three-quarters of the way. Thus when the indicator advances a quarter of a space the fourth hand will come into engagement with a contact, the first hand will leave its contact, and the other two will advance ready to make their contacts in order as will be obvious. The number of spaces, divisions or contacts on the dial is a multiple of the number of hands 1.

2

The dial is not shown as provided with characters in Fig. 1, as that is not necessary according to the present invention. As was the case in my prior patents, each of the contacts 3 is connected with a battery 5 through wires 6, only a few of which are shown. This battery, as well as the hands 1, is connected with the metallic case of the selector A.

10 As each contact is made in succession, one of these branch circuits from the case of the instrument through the battery 5, is completed. They, of course, can be made to operate a drop or the like to indicate the position or place of the hand at that time and annunciate the character without noting the same on the face of the selector. Another way of annunciating the relative position of the dial and indicator, is to use a phono-

20 graphic device for calling out the signal. However, I prefer to use a small electric lamp 7 mounted in the top of each key 8 as indicated diagrammatically at B in Fig. 1. The top of the key is of glass with letters and numerals as desired on the glass or under it. In this case six of the keys are indicated in Fig. 1. In this way it is not necessary to watch any letters on the dial or the positions of the hands. As each character 25 comes into electrical contact through one of the hands 1 it is lighted up and more readily distinguished than when on the dial. These branch circuits 6 are each connected through a lamp filament 7 to a key rod 9 connected with the other terminal of the lamp filament. These key rods in their normal positions are connected with the battery through wires 10 and a conductor 11. When it is desired to send for example the letter "A" 30 that key 8 is pressed down and a contact 12 on that rod 9 breaks the contact with the wire 10 and later comes into contact with a spring 13. This spring is connected through a wire 14 with a circuit 15 which is in series 35 with the conductor 11 connected with the battery. In order to commence to send, a switch 16 is closed to complete this circuit through an electro-magnet 17. This key 8 is kept depressed until the contact is made 40 by the indicator hand and then the circuit is completed over the wire 6, spring 18 (which is a part of each branch 6), lamp 7, rod 9, spring 13, wire 14, circuit 15, magnet 17, conductor 11, battery 5, and the case of the 45 instrument. Now in a manner similar to that set forth in my above mentioned patents this excites the magnet 17 which draws down a lever 19 and makes a contact to complete a circuit 20. This circuit is provided 50 with a battery 21 and a primary 22. The secondary 23 of the same is excited as usual, and a switch 24 therein, being closed to the left as shown in Fig. 1, a signal is delivered 55 through the aerial E.

For the purpose of receiving, the switch 65 24 is thrown over to make a contact 25 and a signal received by the aerial E passes through the tuning coil 26 which is connected with the ground at 27. A variable condenser 28 is shown in circuit with telephone 70 29 and detector 30. I prefer that each of the keys 8 shall also serve as typewriter keys and for that purpose the rod 9 shown in Fig. 3 is connected to operate a lever 31 having a type face 32. Now when the operator at 75 the receiving station hears a dot and dash signal through the telephone that synchronizes with the lighting of a lamp he presses that key at his station. This typewrites the letter called. This is done for each signal until the message is received. In sending the message is also typewritten as sent, preferably but not necessarily.

80 It will be understood that as far as the invention has been described above the relative rotation of the dial and indicator can be provided for in any ordinary way as for example by an ordinary clock train in the selector case. However, certain improvements by which this rotation is provided are 85 shown herein. It will be understood, of course, that although I have shown this mechanism arranged to operate the selector or indicator hands, the dial being stationary, the same principles would be carried 90 out if used to rotate the dial with the hands stationary or to rotate both at different speeds or in different directions. In this 95 case the clock-work for operating the hands is shown as separate from the selector itself. 100

An escapement I is shown having an escapement wheel 44 which is regulated by an oscillating crutch 42. Preferably one pallet of the crutch 42, as 40, is insulated from the remainder of the crutch. The other end 43 of the crutch is of metal and connected through an arm 41 with a circuit 45 in which is a battery 39 and an electro-magnet 49. Both ends of the crutch can be electrically connected if desired, in which case the operation takes place twice for each complete oscillation of the crutch. 105

110 The current from the cell 39 is completed through the case of the instrument and the shaft on which the escapement wheel 44 is mounted only whenever the end 43 of the pallet is in contact with the escapement wheel. In this way, it being understood that the escapement wheel is operated by any usual clock mechanism, an intermittent current is provided for intermittently exciting the electro-magnet 49. This operates a lever 47 which constitutes a ratchet consisting of the end of the lever and a pawl 52 held in position by a spring 51. This ratchet operates a ratchet wheel 53 to which, in the present instance, the arms 1 are secured, so that they move by a step-by-step motion over the 115 120 125

stationary dial. A restraining pawl 48 is shown for an obvious purpose.

As I have shown the indicator as having four hands and shown twenty-eight characters or spaces on the dial, it will be understood that one hundred and twelve contacts are made in one revolution of the indicator. If it revolves once a minute, this gives a little over one half second for each signal. In 10 this case the ratchet wheel 53 will have one hundred and twelve teeth preferably.

It will be understood that the regularity of synchronizing will be more nearly perfect and of longer duration by the use of this 15 mechanism, as practically all friction is eliminated in the clock work. An ordinary stop motion, such as is used on a stop-watch can be employed in connection with it but this is not shown herein. Instead of connecting the battery directly to the case I sometimes prefer to connect it to the ratchet wheel 53, and only when it is time to make a contact. For this purpose I provide on opposite sides of the lever 47, two adjustable 20 contact screws 46 and 55. These are adapted to be moved into position to be engaged by the lever as it swings on its pivot. These are connected with two conductors 56 and 57 which are provided with terminals 58 and 59 respectively. Each of these terminals is 25 adapted to be connected by a switch 60 with the battery terminal. The switch 60 also can connect the battery directly with the case. When sending or receiving this connection 30 through the lever 47 only when that is operative is advantageous to help synchronize.

The clock work is preferably provided with a hair spring 68 for regulating it connected at one end to a spindle 66 and at the 40 other to an oscillating wheel 67 as in ordinary clock work (Fig. 4). This spindle is provided with a projecting arm 69 pressed by a spring 71 up against an adjusting screw 70 which is mounted on a lug 72 on the casing. By the use of this adjusting screw the 45 regulating spring 68 will regulate the clock work so as to make the same synchronize with any selector.

Fig. 5 shows a modification. In this case 50 the hands 1 are also revolved by clock work in the casing and are attached to an escapement wheel 61. This is regulated by a crutch 62 preferably held in position by a spring 63 and controlled by an electro-magnet 64 connected with a circuit 65 similar to the circuit 45 and operating in a similar way. In this case also the hands 1 are 55 shown as connected with contacts 35 by means of a spring in a plane transverse to its direction of motion and adapted to contact with them and to yield to permit it to pass.

In the form shown in Fig. 6 another form 60 of contact is shown, in which each arm 1

also has a yielding terminal 38 for engaging 65 metallic contacts 37 separated from each other by an insulating circle 36.

Although I have illustrated and described only a few forms in which the invention can be embodied, I am aware of the fact that it can be carried out in other forms without departing from the spirit of the invention as expressed in the claims. Therefore, I do not wish to be limited to these particular forms of the mechanism, but

What I do claim is:—

1. In an apparatus for selective signaling, the combination of two members, means for moving one of said members relatively to the other, a series of contacts adapted to be 80 closed and opened in order during such motion, means independent of said members for annunciating the relative position of said members as each contact is made and means for automatically sending a uniform 85 radio signal at each annunciation.

2. In an apparatus for selective signaling, the combination of two members, one having a series of spaces thereon with which the other member is adapted to register, means for moving one of said members relatively to the other, a series of contacts corresponding to said spaces adapted to be closed and opened in order during such motion, electrical means independent of said members for annunciating the relative positions of said members and the space which is registered as each contact is made and means in series with all of said electrical means for sending a uniform signal by radio signaling 100 means upon the making of each of said contacts.

3. In an apparatus for selective signaling, the combination with a dial and indicator rotatable relatively to each other and having a series of contacts adapted to be connected up in order during the rotation of the dial or indicator, a series of electric lamps, one connected with each of said contacts a character adjacent to each of said lamps and 105 adapted to be illuminated thereby, and means in series with all of said lamps whereby a radio signal will be sent whenever any one of said contacts is closed and the lamp 110 illuminated.

4. In an apparatus for selective signaling, the combination with two members rotatable relatively to each other and having a series of contacts adapted to be connected up in order during the rotation of the rotatable 120 member, a branch circuit connected with each of said contacts, a source of electric power connected with all of said contacts, a series of electric lamps, one connected with each of said branch circuits, means whereby 125 said electric lamps can be illuminated as said branch circuits are closed by the rotation of the rotatable member, a character adjacent

- to each of said lamps and adapted to be illuminated thereby, and means operated by said source of power whereby a radio signal will be sent whenever any one of said branch circuits is closed and the lamp illuminated.
5. In an apparatus for selective signaling, the combination with two members relatively rotatable, a series of contacts associated therewith and adapted to be closed in order during the rotation thereof, a branch circuit connected with each of said contacts, each branch circuit being normally open at another point, a push-button for each of said branch circuits having an electric lamp thereon electrically connected with its branch circuit, and means connected with each push-button for closing one of the branch circuits at said other point when the push-button is depressed.
- 10 6. In an apparatus for selective signaling, the combination with two members relatively rotatable, a series of contacts associated therewith and adapted to be closed in order during the rotation thereof, a branch circuit connected with each of said contacts, a push button for each of said branch circuits having an electric lamp thereon connected with the branch circuit, means connected with each push button for closing one
- 15 of the branch circuits when the push button is depressed, and a typewriter lever connected with each push button to be operated upon the depression thereof.
7. In an apparatus for selective signaling, the combination with a dial and indicator relatively rotatable, a series of contacts associated therewith and adapted to be closed in order during the rotation thereof, a branch circuit connected with each of said contacts, a push button for each of said branch circuits, means connected with each push button for closing one of the branch circuits when the push button is depressed, and a typewriter lever connected with each push button to be operated upon the depression thereof.
- 20 8. In a selector for a wireless telegraphing system, the combination of two members concentrically arranged, one rotatably relatively to the other, one of said members having a series of electrical contacts equally spaced apart around the same, dividing the circumference thereof into a plurality of equal series of spaces, the other of said members having a number of hands equal to the number of said series of spaces, the circumferential distance between the ends of two of said hands being equal to the portion of the circumference of said member occupied by one of said series of spaces plus a fraction of the distance between two of the contacts, the circumferential distances between the ends of the other hands being the same with the exception of one pair, and the circum-
- 25 ferential distance between the ends of the hands of that pair being equal to the angle covered by one of said series of spaces less the major portion of a space between two of said contacts, and a series of branch circuits each one connected with one of said contacts.
- 30 9. As an article of manufacture, a selector for the purpose described comprising two concentric members, one rotatable on the center of the other, one of said members having each quarter thereof divided into an equal number of equal divisions, the other of said members having four hands, the circumferential distance between the ends of each pair of adjacent hands except one being equal to one of said quarters in addition to one quarter of the space occupied by one of said divisions, and the circumferential distance between the ends of the other two hands being equal to one of said quarters less three-quarters of the distance covered by one of said divisions.
- 35 10. As an article of manufacture, a selector for the purpose described comprising two concentric elements, one rotatable with respect to the other on the center thereof, one of said elements being divided circumferentially into a plurality of series of equal divisions and the other of said elements having a number of hands equal to the number of said series, the angular distance between two adjacent hands being less than the sum of the angular distances covered by said divisions of one series, and the angular distances between each other two adjacent hands being slightly more than the angular distance covered by the divisions of one series.
- 40 11. As an article of manufacture, a selector for the purpose described comprising two concentric elements, one rotatable on a center relative to the other, one of said elements having a series of equally spaced divisions arranged in a circle, and the other having a plurality of hands, the circumferential distance between each two adjacent hands being slightly more or less than a multiple of the space covered by a division, and the angle between two of said hands being greater than the angle between another pair of the hands.
- 45 12. As an article of manufacture, a selector for the purpose described comprising two members, one rotatable with respect to the other, one of said members having a plurality of series of equally spaced divisions thereon, and the other, a plurality of relatively fixed hands adapted to indicate said divisions, and equal in number to the number of said series, the angular distances between any one of said hands and each of the others being more or less than an exact multiple of the distance occupied by a series of divisions, whereby said hands will always

register with different parts of the respective series of divisions which they indicate.

13. In a device of the character described, the combination of a relatively rotatable dial and indicator, an escapement wheel and an escapement crutch, a lever adapted to be controlled by said crutch, and means connected with said lever for causing a relative step-by-step rotation between the dial and indicator, with a series of circuits each adapted to be closed at one point during

said rotation, and means for connecting all of said circuits with one of the relatively rotary members intermittently when each step of the rotation is made. 15

In testimony whereof I have hereunto set my hand; in the presence of two subscribing witnesses.
